UNITED STATES PATENT OFFICE.

MARTIN KATZ, OF BROOKLYN, NEW YORK.

MOUNTING FOR STORE WINDOWS.

Application filed September 20, 1924. Serial No. 738,908.

To all whom it may concern:

Be it known that I, MARTIN KATZ, citizen of the United States, and resident of Brooklyn, in the county of Kings and State of New York, have invented certain new and useful Improvements in Mountings for Store Windows, of which the following is a specification.

The invention relates generally to the mountings of store windows, having particular reference to means for securing together glass panes at their side edges in angular relation with each other to form corner connections.

In ordinary practice the clamping parts consist in a plurality of screws, nuts and washers, or other loose parts, which are not only difficult in connecting but frequently while in use become disconnected and lost.

The present invention has for an object to provide simple and convenient means for detachably clamping the glass plates together with comparatively few loose connecting parts.

For further comprehension of the invention, and of the objects and advantages thereof, reference is had to the following description and accompanying drawing, and to the appended claims in which the various novel features of the invention are more particularly set forth.

Figure 1 of the drawing is a transverse section taken through the glass panes and connecting parts on the line 1—1 of Fig. 2.

Figure 2 is a sectional view of the clamp connections taken on the line 2—2 of Fig. 1.

Figure 3 is a fragmentary side view of the outer corner member, a portion of the clamping means being shown in section on the line 3—3 of Fig. 2.

Figure 4 is a transverse sectional view similar to that of Fig. 1, but constituting a modification thereof.

In the drawing numeral 10 indicates generally a corner member having a metal body part formed in a channel shaped central portion consisting of a bottom wall 11 and side walls 12, the latter bent outwardly for a short distance and then projecting inwardly to form a pair of angular clamping flanges 13 disposed to support the glass plates 14 at their outer side edges. From the bottom wall 11 a section of the metal is stamped and bent inwardly to form a pair of projective tongues 15, leaving perforations 16 extending through the bottom wall 11.

A clamping member 17, preferably of wood, extends lengthwise of the corner member and is provided with angularly arranged bearing faces 18 disposed to engage the interior side edges of the glass plates for clamping connection with the flanges 13 of the corner member. The clamping member is also provided with an interior and lengthwise-extending groove 19, which slidingly engages in guiding relation the side walls 12 of the corner member. This clamping member is furthermore formed with a perforation 20 which loosely engages the tongues 15, the latter being encircled by a washer 21 arranged to bear against the surface of the clamping member.

The tongues 15 at their projecting ends are provided with aligned perforations forming adjacent side bearing edges 22, the perforations being formed at opposite ends with laterally extended slits 23, by means of which the bearing edges may be preferably bent and made slightly yielding to receive the wedge member 24, the side faces of which may be corrugated as shown for engagement by the side bearing edges of the tongues and which serve to hold the wedge against lengthwise displacement. The latter when driven in place will bear respectively at its opposite side edges against the washer 12 and the wall 25 of the perforation of the tongue, and cause the washer 21 to force the clamp member 17 to engage and clamp the glass plates in connection with the flanges 13 of the corner member 10.

As herein shown in Figs. 1 and 2, a wood filler strip 28 is provided for the channel space of the corner member, extending the full length thereof, and over the outer or exposed surfaces of the latter is provided a metal sheathing or finishing surface 29, the side edges of which are turned over and secured to the corresponding edges of the clamping flanges 13.

In the modification shown in Fig. 4, the construction of the body of the corner member is simplified by the omission of the channel portions 11 and 12 and the wood strip 28, the tongues 14^a being stamped from the convex outer section 12^a. Also the clamping member 17^a is provided with an interior groove 19^a which serves additionally to protect the free end of the tongue 14^a against displacement or interference.

While I have shown the corner and clamping members provided with a single pair of

clamping tongues, it is to be understood that a plurality of similarly operated single or double tongues may be stamped and pressed up from the body of the corner member in accordance with the necessary length thereof.

Having thus described my invention what I claim as new and desire to secure by Letters Patent of the United States is as follows:

1. In a window setting, a connection comprising a body member having a projecting flange disposed to engage an outer face of the glass, a tongue projecting inwardly from said body member, a clamp member arranged to engage the inner face of the glass and provided with a perforation adapted to receive said tongue, and clamping means operating through said tongue and clamp to urge the glass against the flange of said body member.
2. In a window setting, a corner connection comprising a body member having a pair of oppositely projecting flanges disposed to engage the outer faces of angularly arranged panes of glass, a tongue projecting inwardly from said body member, a clamp member arranged to engage the glass in opposition to the projecting flanges of said body member and provided with a perforation adapted to receive said tongue, and clamping means operating through said tongue and clamp member to urge the glass against the projecting flanges of said body member.
3. In a window setting, a corner connection comprising a metallic body member having a pair of oppositely projecting flanges disposed to engage angularly arranged panes of glass, a tongue stamped from a section of said body member and bent to project inwardly therefrom, a clamp member arranged to engage the glass in opposition to the projecting flanges of said body member and provided with a perforation adapted to receive said tongue, and clamping means operating through said tongue and clamp member to urge the glass against the projecting flanges of said body member.
4. In a window setting, a corner connection comprising a metallic body member

having a pair of oppositely projecting flanges disposed to engage angularly arranged panes of glass, a tongue stamped from a section of said body member and bent to project inwardly therefrom, a clamp member arranged to engage the glass in opposition to the projecting flanges of said body member and provided with a perforation adapted to receive said tongue, clamping means operating through said tongue and clamp member to urge the glass against the projecting flanges of said body member, and a sheathing disposed to cover the outer surface of said body member.

5. In a window setting, a corner connection comprising a body member having a pair of oppositely projecting flanges disposed to engage angularly arranged panes of glass, a tongue inwardly projecting from said body member, a clamp member arranged to engage the glass in opposition to the projecting flanges of said body member and provided with a perforation adapted to receive said tongue, said clamp member having a groove extending lengthwise along the inner face thereof, and clamping means operating through said tongue and clamp member to urge the glass against the projecting flanges of said body member, the said clamping means being disposed within the groove of said clamp member.

6. In a window setting, a connection comprising a metallic body member having a projecting flange disposed to engage an outer face of the glass, a tongue stamped from a section of said body member and bent to project inwardly therefrom, a clamp member arranged to engage the inner face of the glass and provided with a perforation adapted to receive said tongue, clamping means operating through said tongue and clamp member to urge the glass against the flange of said body member, and a sheathing disposed to cover the outer surface of said body member and close the opening in the latter formed by the stamping of said tongue.

Signed at New York in the county of New York and State of New York this 17th day of September A. D. 1924.

MARTIN KATZ.
